US0D1001147S

(12) **United States Design Patent** (10) Patent No.: **US D1,001,147 S**
(45) Date of Patent: ** Oct. 10, 2023

(54) **BUILDING CONTROLLER DISPLAY SCREEN WITH A GRAPHICAL USER INTERFACE FOR DISPLAYING A HOME SCREEN**

(71) Applicant: **Honeywell International Inc.**, Charlotte, NC (US)

(72) Inventor: **Ji Zhang**, Shanghai (CN)

(73) Assignee: **HONEYWELL INTERNATIONAL INC.**, Charlotte, NC (US)

(**) Term: **15 Years**

(21) Appl. No.: **29/830,427**

(22) Filed: **Mar. 11, 2022**

Related U.S. Application Data

(63) Continuation of application No. 29/723,580, filed on Feb. 7, 2020, now Pat. No. Des. 947,212.

CLAIM

The ornamental design for a building controller display screen with a graphical user interface for displaying a home screen, as shown and described.

DESCRIPTION

The FIGURE is a front view of a building controller display screen with a graphical user interface for displaying a home screen.

The broken lines showing the display screen and portions of the graphical user interface home screen form no part of the claimed design.
